(57) **CLAIM**

The ornamental design for a packaging material dispenser head, as shown and described.

DESCRIPTION

The patent or application file contains at least one drawing executed in color. Copies of this patent or patent application with color drawing(s) will be provided by the U.S. Patent and Trademark Office upon request and payment of the necessary fee.

FIG. 1 is a top perspective view of a packaging material dispenser head according to a first embodiment;

FIG. 2 is a front-side elevation view thereof, with the rear-side elevation view, left-side elevation view, and right-side elevation view being the same as FIG. 2;

FIG. 3 is a top plan view thereof; and

FIG. 4 is a bottom plan view thereof.

FIG. 5 is a top perspective view of a packaging material dispenser head according to a second embodiment;

FIG. 6 is a front-side elevation view thereof, with the rear-side elevation view, left-side elevation view, and right-side elevation view being the same as FIG. 6;

FIG. 7 is a top plan view thereof; and

FIG. 8 is a bottom plan view thereof.

FIG. 9 is a top perspective view of a packaging material dispenser head according to a third embodiment;

FIG. 10 is a front-side elevation view thereof, with the rear-side elevation view, left-side elevation view, and right-side elevation view being the same as FIG. 10;

FIG. 11 is a top plan view thereof; and

FIG. 12 is a bottom plan view thereof.

The broken lines shown on the drawings depict portions of the packaging material dispenser head that form no part of the claimed design. The dash-dot-dash lines define the bounds of the claimed design and form no part thereof.
